CLAIM

We claim the ornamental design for a washing machine, as shown and described.

DESCRIPTION

FIG. 1 is a front/right-side/top perspective view of our new design for a washing machine;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side plan view thereof; and,

FIG. 7 is a bottom-side plan view thereof.

The broken lines shown in the drawings represent portions of the washing machine that form no part of the claimed design.
